UNITED STATES PATENT OFFICE.

WILLIAM L. MACHUGH, OF PHILADELPHIA, PENNSYLVANIA.

ADJUSTMENT FOR INDUCTANCES OF VARIOMETERS.

Application filed July 23, 1924. Serial No. 728,568.

My invention relates to variometers and particularly to improvement in wave length control for different settings of the variometer.

5 The main purpose of my invention is to provide a novel form of variometer well adapted to the needs of service and easy and inexpensive to manufacture.

A further purpose is to balance the coils of 10 the rotor quantitatively with respect to the coils of the stator, maintaining equal self-inductances in both whatever the adjustment with respect to the quantity of induction.

A further purpose is to have every coil 15 of the rotor and every coil of the stator balanced electrically with respect to every other coil of the variometer by dividing each coil so as to always lie substantially symmetrically with respect to the same point in the 20 rotor axis, a point forming a common center of symmetry for all windings.

A further purpose is to provide an inter-linkage of switch members whereby the number of coils in the rotor and stator, separately 25 adjustable if desired, may be adjustable together in such manner as to maintain a predetermined relation between the numbers of coils simultaneously in circuit on the rotor and on the stator:—or in other words that the 30 number of turns in the rotor and the stator respectively may be increased or reduced together to maintain a condition of numerical balance or numerical relation between them.

A further purpose is to make it possible to 35 accommodate a variometer to lower ranges of wave length than previously without losing its utility for higher wave lengths.

A further purpose is to increase the delicacy of adjustment of the variometer.

40 My invention relates to the processes involved as well as to apparatus shown by which the processes may be carried out.

Further purposes will appear in the specification and in the claims.

45 Figure 1 is a front elevation of a desirable panel providing adjustment of my preferred construction.

Figure 2 is a section of Figure 1 upon line 2—2, the winding being omitted.

50 Figure 3 is a section on line 3—3 of Figure 2.

Figure 4 is a diagrammatic illustration of the preferred form of my invention.

Figure 5 is a diagrammatic illustration

showing the winding whereby my invention 55 may be carried out using any switch preferably the one shown in Figures 1 and 4.

Figure 5^a is a fragmentary view, a part of Figure 5 but with a minor modification.

Figure 6 is a front elevation showing another form of switch, providing if desired, an independent adjustment of the coils of the stator and of the rotor.

Figure 7 is a front elevation of a third form of switch, also providing an optional 65 independent adjustment of the rotor and stator coils.

Figure 8 is a section of Figure 7 taken upon the line 8—8.

Variometers for the purpose of adjusting 70 inductances in radio circuits are of course well known. The rotor is ordinarily given rotation adjustment throughout a range of 180° between the positions for maximum and minimum inductances respectively.

In the position for maximum inductance 75 the rotor coils are in such position that the mutual inductance between the rotor and stator is most effective toward increasing the total inductance of the variometer, while at the other end of the range the mutual inductance is in position to be most effective to decrease total inductance.

In the prior art variometers have been set to different ranges of inductance for variation by the position of the rotor by adjusting the turns of one element to include a larger or smaller number of turns within the active coil length, but so far as I am aware this adjustment in the number of effective 90 turns has never been simultaneous to both stator and rotor.

My invention comprises provision for simultaneous adjustment of the effective turns on both stator and rotor, with an adaptation to alternative independent adjustment of the effective turns of each; provision for maintaining electrical balance between each coil unit of the variometer with every other coil of the variometer; and provision for 100 maintaining throughout the simultaneous adjustment equal inductions in the rotor and stator whereby the rotor and stator are adapted to most nearly neutralize each other when in direct opposition, thereby bringing the lower limits for the different settings most nearly to zero.

The alternative independent adjustments

given to both coils adapt the variometer to extreme delicacy in setting to any desired maximum inductance, and also to obtaining for each one of a number of given maximum 5 inductances several ranges of variation when turning the rotor; for example when a given number of effective coils is in circuit the maximum inductance (existing when rotor is turned to maximum) is nearly the same what-
 10 ever the way in which the number of effective coils is divided between rotor and stator. I provide means for adjusting the relative difference in the self inductance of the active coils upon the rotor and stator while main-
 15 taining the same total number of effective coils and therefore substantially the same maximum inductance, obtaining maximum range with zero bias when there is the same number of effective coils on rotor and stator,
 20 and obtaining a series of progressively smaller ranges each having substantially the same maximum inductance by progressively increasing the relative differences between the self inductances of rotor and stator.
 25 In the upper parts of Figure 2, I have intended to show conventional views of rotor and stator omitting the windings. A minimum of distributive capacity is secured by placing the stator and rotor windings as close together as possible.
 30

The variometer comprises, generally, standards 10, 11 forming supports for a stator 12 initially split in the plane of the paper in Figure 2 so as to permit it to be assembled 35 about the rotor 13. The rotor is rigid with a shaft 14, supported in bearing 15 at one end and with a shaft 16 having a passage 16' through it for the withdrawal of the connecting wires so that the coils in circuit may be 40 varied by connections outside of the rotor. The shaft 16 is supported from the frame in bearings 17.

The shaft 14 affords a mechanical connection between the rotor and an adjusting disc 45 member 18 which is turned by a knurled handle 19. For convenience in assemblage the shaft 14 is made in two parts 20 and 21, united through threads 22 and a sleeve 23 which sleeve forms a conical fitting at 24 with a 50 corresponding opening in the bearing member 25. As both of these parts, the sleeve and the bearing support are of metal, and as one is connected with one end of the rotor coils as shown diagrammatically in Figure 4 at 26 and the bearing member is connected with one 55 end of the coils upon the stator as shown diagrammatically in Figure 4 at 27, the rotor and stator coils are electrically connected by the engagement between any suitable member (such as the sleeve) on the rotor and the 60 surrounding bearing metal of the stator. For maintenance of this connection spring 29 is used.

The dial 18 indicates the degree of movement of the rotor and may be limited to its

usual range of movement 180° as by stops 31, 32.

In the formation of the rotor and stator, I have not intended to indicate the manner of winding whether plain winding or bank winding, for example, as the manner of the winding, as distinguished from the division of the windings into parts (preferably balanced as to turns of each coil on opposite sides of the casing) does not affect my invention.

In the diagram in Figure 4 I have shown my preferred form. The stator winding 33 is split up by taps into a number of turns, divided by tapping points into coil units 35, 36, 37, 38, 39 and 40 with taps between the units leading out at 41, 42, 43, 44, 45 and 46. These taps lead respectively to contacts 47, 48, 49, 50, 51 and 52.

The rotor winding is correspondingly split up into coil units indicated at 53, 54, 55, 56, 57 and 58. Connections lead from the different lines between these coils at 59, 60, 61, 62, 63 and 64 to contacts 65, 66, 67, 68, 69 and 70.

Corresponding coils of the rotor and stator 90 preferably are wound to have substantially equal inductances;—thus, the stator coils 35—40 may or may not be equal to one another in inductance, but preferably are respectively equal to the corresponding coils 95 53—58 of the rotor. When the variometer circuit includes coils 35—40 on the stator and coils 53—58 of the rotor, the inductances of the rotor and stator are equal.

Obviously one of the elements, preferably 100 the stator, might be provided with additional coils having no counterpart on the other element, and adapted for example to be bypassed or adjustably switched into the first coil of the stator. When this is done a convenient arrangement is to have each of the additional coils wound for an inductance equal to the sum of the inductances of coils 35—40. Diagrammatically this arrangement is indicated in Figure 4 at C where switch C is 110 adapted to throw any desired number of the coils C¹, C², C³, C⁴ into the circuit of coil 35; assuming coils 35—40 of equal size and coils C¹—C⁴ each equal to the sum of coils 35—40, it is evident that the settings of the 115 stator include the equivalents of any number of coils from 1 to 30 in number inclusive; further that between the limits of maximum variometer inductances corresponding to 12 coils and 31 coils respectively six ranges of 120 inductance variation is available to the rotor for each maximum number (as 12, 13, 14... 29, 30, 31) of coils, according to the number of the coils in the rotor circuit.

Obviously also the number of these additional coils may be varied to reach any range which may be desired, and by variation of the number of these coils the total inductance represented by each and the number of subdivisions into which each one of the coils 130

may be split up by the taps provided in my invention, great delicacy, flexibility and variety of ranges may be secured.

In Figure 5 I have indicated connections for the several coils which can readily be identified by the points from which the taps run. I show also the division of each coil into two parts symmetrical with respect to the axis of rotation, which is much the preferred form and by which I secure electrical balance of the active coils of the rotor with respect to each other and with respect to the active coils of the stator at all times. Each of the coils is therefore split up as seen into two parts, one of which lies on one side of the axis and the other upon the other side of the axis; the two parts together making up the complete coil. The several parts are shown by prime and second markings, the coils 35, 36, etc., for example, being divided into two parts (turns or sets of turns) each indicated diagrammatically in Figure 5 at 35' and 35², 36' and 36², etc., throughout the stator coils. Likewise the coils 53, 54, etc., of the rotor being divided into two parts each (turns or sets of turns) 53' and 53², 54' and 54² etc., with the intent and result that the parts of any coil always lie equally spaced on opposite sides of the axis and are electrically balanced in their effect upon the correspondingly equally spaced stator coils which may be in action at the time.

I prefer during adjustments to automatically control the relation between the numbers of coils in active duty at any time upon the stator and upon the rotor respectively, and also to secure equality between these numbers, giving at any time the same self inductance to the stator as to the rotor.

This is normally advantageous for several reasons. Equality between the self inductances of the stator and rotor is just the condition at which there is nearest approach to neutralization of both inductances when the stator and rotor are in position to directly oppose one another, giving the nearest approach to zero as the lower limit of each such range. It also secures several specially low ranges having unusually low but progressively higher maximums with extremely low (but progressively higher) minimums.

In the preferred form six coils are shown on the rotor and six on the stator with provision for coupling any number of coils from the one with the same number of coils of the other.

As best seen in Figure 5, I prefer to have the first coils nearest the center on both stator and rotor, working out from the center sequentially with the increase in number of coils.

I have shown in the drawings several advantageous forms of double switches to facilitate easy coupling of the coils in the manner indicated.

Describing first the simplest form, shown in Figures 1 and 2 and diagrammatically in Figures 4 and 5, the contacts or terminals 47-52 and 65-70 are grouped in arcs upon opposite sides of the axis 71 within reach of contact fingers 72, 73 upon strips 74, 75. These strips, relatively electrically insulated, are carried by the disc 76 which is adapted to be turned to bring the fingers to engagement successively with the different contacts.

The opposite ends of these contact strips form contact fingers 77, 78 engaging with arcuate fixed contacts 79, 80 connected respectively with terminals 81, 82 by which the variometer may be connected in the circuit.

When it is desired to have in the variometer circuit one coil of the stator and one coil of the rotor, the contact fingers 72 and 73 will respectively rest upon contact terminals 47 and 65, and to add successive coils the contact fingers will pass in a clockwise direction to terminals 66, 48 and so on, and in every position equality is maintained between the numbers of coils in stator and rotor respectively and therefore in the respective inductances of the rotor and stator.

Obviously the contact fingers may bridge the terminals.

In the somewhat less compact form shown in Figure 6, the contact strips 74' and 75' are spaced axially and turn about spaced axes 71', 71² to engage the contact terminals 47-52 and 65-70. The strips are operatively linked or coupled by a bar 83 so as to travel together and to maintain the same number of coils in the rotor as in the stator.

By disconnecting the coupling bar 83 the switches are free for independent adjustment, permitting a greater variety of combinations and securing some adjustments falling between those available when the strips are coupled together and giving different ranges of inductances.

Each of the switch contacts may be arranged with coil-dead-end trail contacts 84 as seen in fragmentary view 5^a which may be spaced in angular position to control one or more contacts in the rear of the switch. As shown the trailing distances correspond with two contact positions.

In Figures 7 and 8 an alternative double switch is shown that is substantially the equivalent to the form shown in Figure 6 but more compact. This form is one among many structures in which contact devices may be removably linked together to maintain during inductance adjustment an equality or predetermined ratio between the inductances of the rotor and stator with alternatively separate adjustment of these inductances.

In Figure 7 divided contacts 85 and 86 take the place of contact 74, of the other figures. These divided contacts unite through a stem 87 which affords a pivot for both con-

tacts and which has two diameters 88 and 89. The pivot passes through a preferably insulated sleeve 90 and is held in position by nut 91.

5 The double contact 92 corresponding to contact 75 of the other form is movable about the pivot at the point of larger diameter 88 and is insulated from it by sleeve 93 and by disc 94.

10 The contact arms 85 and 86 are both moved by handle 95 and the double contact 92 is moved by a handle 96. So far as thus described these two contact arms, the double contact 85, 86 and the double contact 92 are

15 wholly distinct and separate and may be moved separately to form any of the combinations of which the number of fixed contact plugs and joining coils for the stator and rotor is capable. In order to permit them to

20 be coupled together for common movement I provide a screw pin 96 upon one of the arms which engages within an opening in an insulated lug 97 upon or in the other. When this screw and lug are engaged the contact arms 25 operate in the same way as the contact arms of the form shown in the other figures.

It will be obvious that my invention is independent of the character of the winding, whether bank or otherwise.

30 Its adaptation to maintain during inductance adjustment equal inductances in rotor and stator widens the ranges of the rotor.

Its adaptation to independent adjustment of the inductances of the rotor and stator permits close adjustment to any desired maximum, and permits variation of the rotor ranges without any substantial variation in the total self inductances of the stator and rotor.

40 And finally, the symmetry of every coil with respect to the variometer axis and therefore with respect to every other coil, among other advantages provides electric balance for all settings.

45 In view of my invention and disclosure variations and modifications to meet individual whim or particular need will doubtless become evident to others skilled in the art and I claim all such in so far as they fall within the reasonable spirit and scope of my invention.

Having thus described my invention what I claim as new and desire to secure by Letters Patent is:—

1. In a variometer, a stator inductance and 80 a rotor inductance and connected means for simultaneously adjusting both inductances, the stator and rotor being relatively rotatable independently of the adjustment.

2. In a variometer, substantially equal 85 stator and rotor inductances and connected means for simultaneously adjusting both inductances with maintenance of substantial equality between the adjustments.

3. In a variometer, stator and rotor inductances, an adjustment for the stator inductance, a separate adjustment for the rotor inductance, and means for coupling the adjustments to operate together.

4. In a variometer, a rotor winding divided 95 into sections, a stator winding divided into sections, contacts with which the divisions of the sections are electrically connected and common means for connecting with the respective contacts to secure equality of winding in the rotor and stator respectively independently of rotation of the rotor and for a variety of different total windings.

5. In a variometer, a rotor and stator in series with each other and each having its coil 100 divided into sections, a series of contacts connected with the rotor sections, a series of contacts connected with the stator sections, independently movable switch arms, one engaging each series of contacts to include more or fewer coils in the circuit in each, and means for connecting the switch arms to move in unison.

6. In a variometer, a rotor coil divided into sections, a plurality of switch contacts to 90 which the section terminals are connected, arranged to be shaped, a stator winding divided into sections, a plurality of switch contacts to which the stator section terminals are connected, arranged about the same center as the arc of the rotor contacts, switch fingers bearing upon the respective contacts and insulated from each other, common rotor means for the switch fingers and contacts made by said switch fingers at the opposite ends thereof from the first contacts.

WILLIAM L. MACHUGH.
